GASHOLDER OF THE WATERLESS TYPE

Walter Pechstein, Dortmund, Germany, assignor
to the firm Aug. Klönne, Dortmund, GermanyApplication August 24, 1934, Serial No. 741,340
In Germany June 9, 1934

9 Claims. (Cl. 48—174)

My invention relates to gasholders of the waterless type comprising a piston-like closure member axially movable therein and sealing means interposed between said closure and the inner wall of the holder. In practice gas-holders of this kind are always constructed so that there is a closed chamber above the piston-like closure member or plunger and gas leaking past the plunger forms with air an explosive mixture in this chamber unless adequate provision is made for ventilation.

There have been proposals for dispensing with the roof which forms the top of this chamber, but it was hitherto not found practicable to adopt these proposals, because omission of the roof involved excessive exposure of the sealing means to atmospheric influences, and in cold weather deposits of rain and snow are liable to freeze on the exposed inside wall of the holder, preventing upward movement of the plunger.

According to my invention there is substituted for the ordinary roof a system of vertical or inclined baffles, whereby rain, snow or hail, generally falling aslant, is caused to descend approximately vertically after passing the baffles, so that it is kept clear of the wall and falls in the main upon the central part of the plunger, from which it can be removed in known manner by syphoning. The top of the plunger may with advantage be dished, so that the water gravitates towards the centre, whence it can be removed to the interior of the holder by means of a single syphon, not shown. With this arrangement there is no risk of the plunger becoming askew.

The baffles are made of such width (from top edge to bottom edge) as may be required to deflect the rain from the holder wall, and there is ample clearance between them to prevent the formation of an explosive mixture.

Numerous ways of arranging the baffles are possible. A good method is to make them form cells, which may be square, rhomboid, hexagonal, triangular or circular. In some cases a simple arrangement of concentric rings may be adequate.

The system of baffles may be convex, concave or horizontal. The baffles may be of comparatively light construction, as they are not subjected to any particular stress.

Examples are shown in the annexed drawings, in which

Fig. 1 is a vertical section of a gas holder with a roof according to the invention.

Fig. 2 is a vertical section, showing two somewhat different constructions of the roof.

Figs. 3—6 are plan views showing four modified constructions of the roof.

Figs. 7 and 8 are vertical sections showing other examples.

Referring first to Fig. 1, the gas holder or tank casing 1 has therein a dished plunger or piston-like closure member 2 with a cylindrical skirt 3 of comparatively considerable length. A framework 4 surrounds the skirt, and is fixed to the same, carrying the rollers 5 and the packing ring 6, which preferably bears elastically against the wall of the holder. A circular platform 7 is fixed between the skirt 3 and the packing ring 6. Workmen attending to the packing and rollers can walk on this platform. The platform may also be constructed to form a ballast carrier.

The roof consists of a convexo-concave system of circular baffles 8, with the concave side facing upwards. The baffles are inwardly inclined from top to bottom, the angle of inclination increasing from the central part of the roof towards the rim. On the other hand, the distance between the baffles decreases from the centre towards the rim. At the rim there is a cover 9, downwardly inclined towards the circumference.

Fig. 2 shows two modifications in which the roof is flat. In the modification shown on the left hand side the baffles are vertical, in that shown on the right they are inclined as in Fig. 1.

Figs. 3—6 illustrate various forms of construction in which the baffles form cells. Fig. 3 shows a system of circular and radial baffles. Fig. 5 shows a form of lattice work, forming parallelograms.

Figs. 4 and 6 show squares and hexagons respectively. It will be understood that various other arrangements may be adopted.

Fig. 7 shows a construction in which the roof is concavo-convex, with the convex side facing upwards. This has the advantage of securing an increased flow of air through the upper part of the holder. As indicated by arrows at X, wind striking the roof on one side is deflected downwards by the baffles, and passes out on the other side, as indicated by arrows at Y. The arrows Z in this figure indicate a fall of rain or snow, and it will be clear that the baffles (whether disposed as shown in this figure or in any of the other ways described) to a large

extent prevent the rain from reaching the inside wall surface of the holder.

Fig. 8 shows a modification in which a ventilating shaft 10 surrounds the system of baffles with-
5 in the circumference of the cover 8. This shaft 10 prevents the accumulation of an explosive mix-
ture under the cover 8 in the room 11. The
height and diameter of the shaft are so propor-
tioned that rain falling at the most acute angle
10 which may be expected to occur will be deflected
from the wall of the holder by the shaft.

I claim:

1. A gasholder of the waterless type, comprising
15 a tank casing, a piston-like closure member
movable in said tank casing, sealing means inter-
posed between said closure and the inner wall
of the casing, a ring-shaped inwardly projecting
cover arranged on the upper end of the casing,
20 and a plurality of baffles spaced apart and ar-
ranged in the non-covered opening adjacent the
ring-shaped cover and adapted to deflect rain,
hail and snow from the inside surface of the cas-
ing wall and the sealing means.

2. A gasholder of the waterless type, comprising
25 a tank casing, a piston-like closure member
movable in said tank casing, sealing means inter-
posed between said closure and the inner wall of
the casing, a ring-shaped inwardly projecting
cover arranged on the upper end of the casing,
30 and a plurality of vertical baffles spaced apart and
arranged in the non-covered opening adjacent
the ring-shaped cover and adapted to deflect rain,
hail and snow from the inside surface of the cas-
ing wall and the sealing means.

3. A gasholder of the waterless type comprising
35 a tank casing, a piston-like closure member
movable in said tank casing, sealing means inter-
posed between said closure and the inner wall
of the casing, a ring-shaped inwardly projecting
cover arranged on the upper end of the casing,
40 and a plurality of inwardly inclined baffles spaced
apart and arranged in the non-covered opening
adjacent the ring-shaped cover and adapted to
deflect rain, hail and snow from the inside sur-
face of the casing wall and the sealing means.

4. A gasholder of the waterless type, comprising
45 a tank casing, a piston-like closure member
movable in said tank casing, sealing means inter-

posed between said closure and the inner wall
of the casing, a ring-shaped inwardly projecting
cover arranged on the upper end of the casing,
5 and a plurality of baffles forming cells and ar-
ranged in the non-covered opening adjacent the
ring-shaped cover and adapted to deflect rain,
hail and snow from the inside surface of the cas-
ing wall and the sealing means.

5. A gasholder of the waterless type, comprising
10 a tank casing, a piston-like closure member
movable in said tank casing, sealing means inter-
posed between said closure and the inner wall of
the casing, a ring-shaped inwardly projecting
cover arranged on the upper end of the casing,
15 and a plurality of baffles forming concentric
rings and arranged in the non-covered opening
adjacent the ring-shaped cover and adapted to
deflect rain, hail and snow from the inside sur-
face of the casing wall and the sealing means.

6. A gasholder of the waterless type, comprising
20 a tank casing, a piston-like closure member
movable in said tank casing, sealing means inter-
posed between said closure and the inner wall of
the casing, a ring-shaped inwardly projecting
cover arranged on the upper end of the casing,
25 and a plurality of baffles spaced apart and ar-
ranged in concave form in the non-covered opening
adjacent the ring-shaped cover and adapted to
deflect rain, hail and snow from the inside sur-
face of the casing wall and the sealing means.

7. A gasholder of the waterless type, comprising
30 a tank casing, a piston-like closure member
movable in said tank casing, sealing means inter-
posed between said closure and the inner wall of
the casing, a ring-shaped inwardly projecting
cover arranged on the upper end of the casing,
35 and a plurality of baffles spaced apart and ar-
ranged in convex form in the non-covered opening
adjacent the ring-shaped cover and adapted to
deflect rain, hail and snow from the inside surface
40 of the casing wall and the sealing means.

8. A gasholder according to claim 1, in which
the ring-shaped cover is provided with a ventilat-
ing shaft surrounding the baffles.

9. A gasholder according to claim 5, in which
the spaces between the rings decrease in width
from the center towards the rim.

WALTER PECHSTEIN.
